(21) Appl. No.: **29/169,087**

CLAIM

(22) Filed: **Oct. 15, 2002**

I claim the ornamental design for a name plate of a suitcase having the function of a sewing kit, as shown and described.

(51) **LOC (7) Cl. 20-03**

DESCRIPTION

(52) **U.S. Cl. D20/19; D3/20**

FIG. 1 is an upper perspective view of the name plate of a suitcase having the function of a sewing kit showing my design.

(58) **Field of Search D3/20, 208; D9/423;**

FIG. 2 is a front view thereof;

D20/19, 22, 27, 99; 40/653, 1.5, 124.2,
546; 116/2, DIG. 1; 206/38.1; 223/106;
362/812

FIG. 3 is a back view thereof;

FIG. 4 is a left side view thereof;

FIG. 5 is a right side view thereof;

FIG. 6 is a top view thereof;

FIG. 7 is a bottom view thereof; and

FIG. 8 is a top perspective view thereof, showing an extended embodiment and exposing the name tag thereof; and,

FIG. 9 is a bottom perspective view thereof, showing the opposite side of the extended embodiment and exposing the sewing kit thereof.
